CONVEYING SYSTEM

Nels H. Sandberg and Henry O. Ronning, Minneapolis, Minn., assignors to Waldorf Paper Products Company, St. Paul, Minn., a corporation of Minnesota

Application November 29, 1945, Serial No. 631,581

11 Claims. (Cl. 164—61)

1

Our invention relates to an improvement in conveying systems wherein it is desired to provide a means of conveying individual stacks of sheets from one machine to another.

In the formation of container blanks such as those used for shipping purposes, it is common practice to cut large sheets into a series of smaller sheets which are fed individually into the blank forming machine. The large sheets are usually fed into a machine which cuts the sheet into smaller sections and deposits the sheet into a series of receiving bins which are usually separated by a divider plate. The divider plates are ordinarily required between adjacent stacks of paper board in order to prevent the sheets of one stack separate from the sheets of the next adjacent stack or stacks. In the past, it has been necessary to remove the stacks of sheets from each bin and to carry the blanks to a conveyor. Thus, time and work are required to accomplish this purpose.

It is the object of the present invention to provide a movable conveyor platform which is movable between two extreme positions. In one extreme position, the platform is positioned adjacent the cutting or slitting machine to receive sheets therefrom. Above the platform are mounted dividing partitions which extend down into proximity with the movable platform. By operating the cutting apparatus in the ordinary way, piles of sheets are deposited upon the movable platform and the series are separated by means of the fixed partitions. When the piles on the movable platform reach a pre-determined height, the platform is moved to another position beyond the ends of the fixed partitions. When in this position, the individual stacks of sheets may be easily pushed onto the conveyor which delivers the sheets in stacks to the feed mechanism of the blank forming machine.

A feature of the present invention resides in providing a movable conveyor platform which is movable into or out of alignment with a second conveyor. While in one position, the movable platform may receive sheets from the sheet cutting or slitting apparatus. While in the other position, the movable platform may act as a part of a continuous conveyor.

A feature of the present invention resides in supporting one or more divider plates above the level of the movable platform and in fixed relation to the slitting apparatus. As a result, the platform may be moved from one position to another without affecting the position or adjustment of the dividing partitions.

2

A further feature of the present invention resides in mounting partition plates adjustably to the delivery end of a slitting or cutting apparatus. When it is desired to change the width of the cut sheets, it is only necessary to change the position of the cutting rollers and to similarly adjust the position of the partitions. Thus, the partitions may be set to receive sheets of any desired width and to hold one stack of sheets separate from one or more adjacent stacks of sheets.

A further feature of the present invention resides in the provision of a means for mechanically moving the movable platform from one position to another. The cutting or slitting apparatus may be used for fibreboard sheets, card-board, corrugated board, or laminated board. The stacks of sheets piled upon the movable platform are extremely heavy. In order to move the movable platform, it is only necessary to close a circuit to the driving motor which acts to drive the conveyor in either direction the necessary distance to move the movable platform into or out of alignment with the conveyor.

These and other objects and novel features of our invention will be more clearly and fully set forth in the following specification and claims.

In the drawings forming a part of our specification, Figure 1 is a top plan view of our apparatus, showing the construction thereof.

Figure 2 is an elevational view of our apparatus.

Figure 3 is a side elevational view of our apparatus, the view being taken at right angles from the position of Figure 2.

Our conveying system acts to operatively connect a slitting apparatus A with a conveyor B, preferably leading to the feed mechanism of a container blank forming apparatus C. The apparatus includes a movable conveyor platform which is illustrated in general by the letter D.

The slitting or cutting apparatus A may be of any desired type to produce the necessary result. The slitter includes a supporting frame 10 which supports a pair of transversely extending parallel shafts 11 and 12. The shaft 11 supports a series of adjustable spaced cutting or slitting rollers 13. The rollers 13 cut against cooperating rollers 14, which may be grooved to cooperate with the cutting rollers or which may in themselves comprise cutting rollers. When a sheet is fed between the rollers 13 and 14 the sheet is cut or slit longitudinally into a series of sections depending upon the position of the rollers 13 upon their respective shafts 11 and 12.

The frame 10 also supports a pair of parallel shafts 15 and 16. The shaft 15 supports a series of spaced rollers 17. The shaft 16 supports an elongated roller 19 which may cooperate with the rollers 17 to draw the sheet through the cutting or slitting apparatus, knives 13 and 14.

A track or guide 20 is supported on the frame 10, substantially parallel to the axes of the various shafts described. This track or guide 20 acts as a support for the partition forming plates 21 which separate the stacks of blanks. The partition plates 21 are supported by brackets 22 which slidably engage the upper edge of the track or guide 20. The brackets 22 are held in adjusted position by hand adjusted set screws 23 or by any suitable clamping apparatus.

The movable conveyor platform D comprises a substantially rectangular frame 24 which is supported by flanged rollers 25 and 26 mounted upon transversely extending shafts 27 and 29, and supported by suitable bearings such as 30 and 31, secured to the lower surface of the frame 24. The flanged rollers 25 and 26 are engaged in a pair of parallel tracks 32 which guide the movement of the movable conveyor platform.

Corner posts 33 extend upwardly from the frame 24 to support a second rectangular frame 35. This frame 35 supports a pair of substantially parallel angle members 36, mounted in opposed relation near opposite ends of the frame 35. A series of parallel rollers 37 are supported by the angle members 36, the central shafts 39 of these various rollers extending through the angle members 36 and being supported thereby.

A series of upright frame members 40 are adjustably secured to the frame 24 and to the frame 35, to extend upwardly above the level of the partition members 21. These uprights 40 provide an abutment against which the various sheets may be stacked. The feed rollers 17 and 19 feed the sheets through the slitters with some force, and the slit sheets slide into the compartments between adjacent partitions 21. The movement of the sheets is halted by the upright abutments 40 which hold the sheets in proper stacked formation.

The conveyor platform D is of such a height that it may extend partly under the splitting apparatus of the splitter A. The abutments 40 may be moved with the platform towards or away from the feed rollers 17 and 19 so as to receive sheets of varying lengths. Thus, the position of the platform may be adjusted to suit sheets of varying lengths as well as varying widths.

In order to move the conveyor platform from one position to another, we provide a reversible electric motor 41 secured to the frame 24. This motor 41 actuates a belt or chain 42 which connects a pulley or sprocket 43 on the motor 41 to a pulley or sprocket 44 on the shaft 27. Accordingly, upon closing the circuit to the motor 41 the chain or belt 42 may operate in either direction to rotate the shaft 27 in a clockwise or counter-clockwise direction. The platform D may thus be moved into position adjacent the splitter A and beneath the partition plates 21, or may be moved into alignment with the conveyor B.

The conveyor B may be of any suitable or desired type. As illustrated it comprises a frame 45 supported by legs or other supporting means 46. A pair of parallel angle members 47 are supported upon the frame 45. Conveyor rollers 49 are mounted between the angle members 47, the

shafts 50 of these rollers having their support in a vertical flange of each angle member 47. The rollers 49 are freely rotatable to enable the stacks of sheets to be readily moved upon the same.

The conveyor B in preferred form leads to the motor driven conveyor 51 of a blank forming apparatus or similar machine. The blanks are usually individually placed upon the driven conveyor leading to the blank forming machine manually. Thus, as the sheets of each stack are used up by placing the same upon the driven conveyor 51 another stack may be pushed into feeding position.

In the use of our apparatus the movable platform D is placed into position to receive sheets from the splitter A and the knives of the splitter are adjusted to provide the proper width of sheet. The partition plates 21 are aligned with the knives so as to separate the adjacent stacks of sheets during the stacking operation. These partitions are important, as they prevent the sheets of one stack from becoming interleaved with the sheets of an adjacent stack.

When stacks of the proper height are attained, the movable platform D is moved into alignment with the conveyor B leading to the blank forming machine C. Movement of the platform is accomplished by closing the circuit to the drive motor 41. When the movable conveyor section is aligned with the conveyor B the stacks of sheets may be easily pushed onto the conveyor B. The movable platform D may then be returned into its position in close proximity with the splitter A to receive more sheets.

In accordance with the patent statutes, we have described the principles of construction and operation of our conveyor system, and while we have endeavored to set forth the best embodiment thereof, we desire to have it understood that obvious changes may be made within the scope of the following claims without departing from the spirit of our invention.

We claim:

1. A sheet conveying mechanism in combination with a sheet splitting apparatus and a blank forming apparatus, comprising a movable conveyor platform, means guiding said platform towards and away from said splitting apparatus, a conveyor leading to the blank forming apparatus, the directions of travel of said splitting apparatus and said conveyor being at right angles, said conveyor being aligned with said platform when the same is moved away from said splitting apparatus.

2. A sheet conveying apparatus for use in combination with a sheet splitter and a conveyor, the directions of travel thereof being at right angles, the apparatus comprising a movable conveyor platform movable towards or away from a sheet splitter, said platform being arranged to receive sheets from said splitter when moved adjacent the same, said conveyor being spaced from said splitter, said conveyor platform being movable into alignment with said conveyor when spaced from said splitter.

3. A sheet conveying apparatus for use in combination with a sheet splitter and a conveyor, the directions of travel thereof being at right angles, the apparatus comprising a movable platform, means movably supporting said platform, means guiding the movement of said platform towards and away from said splitter, said platform when in position adjacent said splitter being in position to receive sheets therefrom, said conveyor being offset from said platform when in

sheet receiving position, said platform being movable into alignment with said conveyor when moved away from said splitter.

4. A sheet conveying apparatus for use in combination with a sheet splitter and a conveyor, the directions of travel thereof being at right angles, the said conveyor comprising a movable platform, conveyor rollers mounted upon the said platform, means guiding said platform for movement towards or away from said splitter, said platform being adapted to receive sheets fed through said splitter when positioned adjacent the splitter, said sheets dropping upon said conveyor rollers, said conveyor being offset from said platform when said platform is in sheet receiving position, said platform being movable into alignment with said conveyor.

5. A sheet conveying apparatus for use in combination with a splitter and conveyor, the apparatus comprising a movable table movable toward or away from said splitter, said table being positioned to receive sheets from said splitter when positioned adjacent the same, said table being movable into alignment with said conveyor, and partition means which separate the slit sheets supported above said table when said table is adjacent said splitter.

6. A sheet conveying apparatus in combination with a splitter and conveyor, said apparatus comprising a movable conveyor table movable toward and away from said splitter, said table being adapted to receive split sheets from said splitter when positioned adjacent the same, partition members supported above said table, said partitions holding said stacks in proper position upon said table when said table is adjacent said splitter, said table being movable into alignment with said conveyor, said table being moved beyond the ends of said partitions when aligned with said conveyor.

7. A sheet conveying apparatus for use in combination with a sheet splitter and a conveyor, said apparatus comprising a movable table movable towards and away from said splitter, partition members which separate the split sheets extending vertically above said table and fixed relative to said splitter, said table being offset relative to said conveyor when in sheet receiving position adjacent said splitter, said table being movable into alignment with said conveyor, said table being movable beyond the ends of said partition members.

8. A conveying apparatus for use in combination with a sheet splitter and conveyor, said apparatus comprising a movable table movable into and out of sheet receiving position relative to said splitter, vertical partition members which

separate the split sheets secured in fixed relation to said splitter and extending upwardly from said table to separate the split sheets into separate stacks, said table being movable beyond the ends of said partition members, said table when in the latter position aligning with said conveyor.

9. A conveying apparatus for use in combination with a sheet feeding device and a sheet receiving conveyor, the apparatus comprising a conveyor table, having a series of substantially parallel rollers supported thereon, means movably supporting said table to move toward or away from said sheet feeding device, a series of vertically extending partitions secured adjacent 10 said sheet feeding apparatus to separate stacks of the sheets from each other as the sheets are fed and stacked upon said rollers on said table, means for moving said table from a position adjacent said feeding apparatus to a point beyond the ends of said partition members, said conveyor comprising a series of rollers substantially parallel to the rollers on said table, said conveyor being positioned beyond the ends of said partition members to become aligned with said table when said table is moved beyond said partition members.

10. A conveying device for use in combination with a sheet feeding apparatus and a sheet receiving conveyor, said device including a movable table movable from a sheet receiving position adjacent said feeding apparatus to a position remote therefrom, a series of transversely adjustable partition members supported adjacent said sheet feeding apparatus to guide the said sheets into stacked relationship upon said table, said table in remote position being beyond the ends of said partition members and aligned with said conveyor.

11. A sheet stacking apparatus comprising a series of transversely adjustable splitting knives, feed rollers adjacent said splitting knives to pull the sheets through said splitting knives, a support for receiving the split sheets, and partition members transversely adjustable to align with 40 said splitting knives and to guide the split sheets into stacked formation.
